UNITED STATES PATENT OFFICE.

WALLER L. KAUFMANN, OF SANTA ANA, CALIFORNIA.

DESIGN FOR AN ELECTRIC-LAMP BRACKET.

49,995.

Specification for Design.

Patented Dec. 5, 1916.

Application filed October 3, 1916. Serial No. 123,595. Term of patent 3½ years.

To all whom it may concern:

Be it known that I, WALLER L. KAUFMANN, a citizen of the United States, residing at Santa Ana, in the county of Orange and State of California, have invented a new, original, and ornamental Design for an Electric-Lamp Bracket, of which the following is a specification, reference being had to the accompanying drawing, forming part thereof.

Figure 1 is a side elevation of an electric

lamp bracket, showing my new design. Fig. 2 is a plan view thereof. Fig. 3 is an end elevation.

I claim:—

The ornamental design for an electric lamp bracket, as shown.

WALLER L. KAUFMANN.

Witnesses:

CARL H. KAUFMANN,
D. N. KELLY.
